United States Patent Office

Des. 195,658
Patented July 9, 1963

195,658

FROZEN CONFECTION

James S. Merritt, Kansas City, Mo., assignor to The James S. Merritt Company, Kansas City, Mo., a corporation of Missouri

Filed Feb. 27, 1962, Ser. No. 68,999

Term of patent 14 years

(Cl. D82—2)

Fig. 1.

Fig. 2.

Fig. 3.

Fig. 4.

FIG. 1 is a side elevational view of a frozen confection showing my new design;

FIG. 2 is a side elevational view thereof as seen from the left of FIG. 1;

FIG. 3 is a top plan view; and

FIG. 4 is a bottom plan view thereof.

The essential features of my design reside in the portions shown in solid lines on the drawing.

I claim:

The ornamental design for a frozen confection, as shown and described.
